TYPE BAR BEARING

Henry L. Tholstrup, Rochester, N.Y., assignor to Commercial Controls Corporation, Rochester, N.Y., a corporation of Delaware

Application February 18, 1959, Serial No. 794,121

5 Claims. (Cl. 197—38)

This invention relates to an improved bearing for type bars.

The type bars of a typewriter are mounted in a type bar segment by a steel fulcrum wire which passes through a type bar fulcrum hole at the end of the type bar opposite the type head. The fulcrum wire, therefore, constitutes the bearing on which the type bars rock during the typing operation. Since the fulcrum wire is seated in a groove which follows the arc of the sector comprising the type segment, it is curved throughout its length with the result that the type bar fulcrum hole, which is cylindrical, is in point contact therewith rather than in the more ideal line contact. The point contact between the cylindrical type bar fulcrum hole and the conventional curved fulcrum wire results in such rapid wear of the type bar fulcrum hole that the type bars so mounted will not operate satisfactorily beyond about a half million operations before replacement becomes necessary.

It is, therefore, the principal object of this invention to provide a type bar bearing which will overcome the deficiencies of the conventional structures and which will greatly extend the operating life of a type bar before replacement is required.

The objective of the invention is attained by providing a bearing insert for the type bar fulcrum hole, which insert is characterized by a true cylindrical bearing surface which provides for perfect line contact with the type bar fulcrum hole.

It is a further object of the invention to provide a larger bearing surface for a type bar than that heretofore provided by the conventional fulcrum wire. Withal, it is the purpose of the invention to provide an improved type bar bearing which is compatible with the design and dimensions of the type segments and fulcrum wires now in use.

It is still a further object of the invention to provide an improved type bar bearing which can be cheaply produced and installed in typewriters without substantial modification of existing typewriter elements.

These and other objects and advantages of the invention will appear from a perusal of the description which is to follow when read in light of the drawings forming a part hereof, in which drawings like reference numerals indicate like parts, and in which:

Fig. 1 is a sectional view through a type bar segment showing the mounting of a type bar and its immediately associated operating linkage;

Fig. 2 is a rear plan view of a fragment of a type bar segment;

Fig. 3 is a cross-sectional view on line 3—3 of Fig. 2 showing, moreover, a fragment of a type bar mounted therein;

Fig. 4 is a more or less diagrammatic view of a conventional type bar in relation to its fulcrum wire;

Fig. 5 is an enlarged plan view of a type bar bearing insert; and

Fig. 6 is an enlarged elevational view of the bearing insert of Fig. 5.

2

It is conventional practice to mount the type bars of a typewriter in a type bar segment by means of a steel fulcrum wire on which the type bars are adapted to rock. In Fig. 1, a type bar 10 has a type bar fulcrum hole 12 formed in the end thereof which is remote from the type head. A type bar segment 14 (Fig. 2) has formed in the perimeter of the arcuate base thereof a plurality of slots 15 each of which is adapted to receive the end of a type bar. The slots 15 are intersected by a fulcrum wire groove 17 such that when the fulcrum holes 12 of the type bar are disposed within the fulcrum wire groove 17, a fulcrum wire 16 can be threaded through the type bar fulcrum holes and through the fulcrum wire grooves 17 of the type bar segment 14. The segment wire 16 accordingly serves as a fulcrum on which the type bars are rocked during the typing operation.

In Fig. 1, the type bar 10 is actuated about its fulcrum into printing position by means of a sub-lever 18, the upper end of which is connected by means of a link 20 to a bell crank lever 22 which is pivoted at 24 to its related type bar 10. The opposite end of the bell crank lever 22 is articulated at 26 to an arm 28 mounted on a fulcrum 30, forming a toggle type bar actuator. A spring 32 normally holds the type bar operating mechanism in the position shown in Fig. 1.

It can be seen by reference to Fig. 2, that the fulcrum wire 16 presents a curved or toroidal surface with the result that the bearing relationship between the cylindrical fulcrum fulcrum holes of the type bars and the fulcrum wire is such as indicated in Fig. 4, wherein it can be seen that by reason of the curved state of the fulcrum wire, three points of contact x, y and z are established between the cylindrical fulcrum hole of the type bar 10 and the fulcrum wire 16. It is obvious that the bearing points x, y and z will be subject to wear, while other of the confronting, though spaced surfaces, will receive little or no wear. The eccentric relationship of the bearing surfaces will soon result in an enlargement of the fulcrum hole in the type bars such that the type bar will no longer maintain the type face in proper alignment.

The invention herein is predicated on the provision of a true cylindrical bearing surface as the fulcrum for each type bar. Accordingly, each of the type bars is fitted with a cylindrical bearing insert 38 such as that illustrated in Figs. 5 and 6. Conventionally, the fulcrum hole of the type bar is .094 of an inch in diameter, which is the diameter required by the fulcrum wire. Accordingly, the fulcrum hole is enlarged to about .187 of an inch to receive the bearing insert. The bearing insert 38 is in the form of a bushing having a thickness equal to the thickness of the type bar in the area of the type bar fulcrum hole. The internal diameter of the bearing insert is of such size as to fit snugly the fulcrum wire 16, and if the fit of the bearing insert on the fulcrum wire is sufficiently tight, the bearing insert will be held against rotation. In a typical embodiment, the bushing 38 has an external diameter of .187 of an inch and a concentric bearing hole whose diameter is about .094 of an inch.

In order to insure that the bearing insert will not rotate on the fulcrum wire after it has been installed, it may be desirable to form the bearing insert with one or more lateral holding lugs. The bearing insert illustrated in Fig. 6 has a pair of lateral lugs 42 and 44 extending from the opposite faces thereof. The lugs 42 and 44, or either of them if only one is provided, are adapted to seat in a slot 46 (Fig. 3) which intersects the fulcrum wire groove 17. The slot 46 is in the order of .080 of an inch in width and the lugs 42 and 44 should, therefore, be not substantially less in width in order to hold the bearing inserts against rotation.

The bearing inserts may be formed of any suitable material. While steel and steel alloys have been em-

ployed with good results, the most satisfactory bearing inserts have been those molded of relatively hard organic plastic materials. In this latter category, epoxy resin, nylon and a moldable polymer of trifluorochloroethylene, commercially available under the Minnesota Mining and Manufacturing Company's trade name Kel-F, have been successfully employed. Nylon lends itself particularly well to precision molding, and tests made on a complete set of nylon bearing inserts in an automatic power operated typewriter indicate that more than ten million type bar operations may be expected of a properly fitted insert.

Not only does this invention eliminate the difficulties arising from eccentric bearing surfaces, but it also provides a larger bearing area between the type bar and its fulcrum, thereby better distributing the operating load.

While the fundamentally novel features of the invention have been illustrated and described in connection with a specific embodiment of the invention, it is believed that this embodiment will enable others skilled in the art to apply the principles of the invention in forms departing from the exemplary embodiment herein, and such departures are contemplated by the claims.

I claim:

1. In combination, a type segment having an arcuate perimeter provided with type bar slots and a segment wire groove intersecting said slots, a type bar having a cylindrical fulcrum passage at one end thereof seated in one of said type bar slots, a cylindrical bearing insert within said fulcrum passage, a fulcrum wire in said segment wire groove and extending through said cylindrical insert, and means for holding said bearing insert against rotation on said fulcrum wire.

2. In combination, a type segment having an arcuate perimeter provided with type bar slots and a segment wire groove intersecting said slots, a type bar having a cylindrical fulcrum passage at one end thereof seated in one of said type bar slots, a cylindrical bearing insert within said fulcrum passage, a fulcrum wire in said segment wire groove and extending through said cylindrical insert, and a laterally extending lug on said bearing insert in engagement with said type segment for holding said bearing insert against rotation on said fulcrum wire.

3. In combination, a type segment having an arcuate perimeter provided with type bar slots and a segment wire groove intersecting said slots, a type bar having a cylindrical fulcrum passage at one end thereof seated in one of said type bar slots, a cylindrical bearing insert within said fulcrum passage, a fulcrum wire in said segment wire groove and extending through said cylindrical insert, a slot intersecting said segment wire groove, and a lug on said bearing insert adapted to engage said slot for holding said bearing insert against rotation on said fulcrum wire.

4. In combination, a type segment having an arcuate perimeter provided with type bar slots and a segment wire groove intersecting said slots, a type bar having a cylindrical fulcrum passage at one end thereof seated in one of said type bar slots, a cylindrical molded nylon bearing insert within said fulcrum passage, a fulcrum wire in said segment wire groove and extending through said cylindrical insert, and means for holding said bearing insert against rotation on said fulcrum wire.

5. In combination, a type segment having an arcuate perimeter provided with type bar slots and a segment wire groove intersecting said slots, a type bar having a cylindrical fulcrum passage at one end thereof seated in one of said type bar slots, a cylindrical nylon bearing insert within said fulcrum passage, a fulcrum wire in said segment wire groove and extending through said cylindrical insert, a slot intersecting said segment wire groove, and a laterally extending lug on each of the opposite faces of said bearing insert adapted to engage said slot for holding said bearing insert against rotation on said fulcrum wire.
